UNITED STATES PATENT OFFICE.

THORNTON McDUFFEY YANCEY, OF OAK PARK, ILLINOIS, ASSIGNOR TO WESTERN ELECTRIC COMPANY, INCORPORATED, OF NEW YORK, N. Y., A CORPORATION OF NEW YORK.

MATERIAL-WORKING APPARATUS.

Application filed September 3, 1926. Serial No. 133,381.

This invention relates to material working apparatus, and more particularly to strand twisting or stranding apparatus used in the manufacture of multi-strand cables.

5 One object of this invention is to provide a material working apparatus having a simple and efficient tension device for maintaining the material being worked under substantially equal uniform predetermined conditions of tension.

Other objects of this invention are to provide in a material working apparatus a material advancing apparatus with which the material may be easily and quickly associated and maintained.

In accordance with the general features of this invention as applied to a stranding apparatus used in the manufacture of telephone cables, there is provided an auxiliary capstan comprising a plurality of individual grooved strand or wire drawing drums uniformly spaced about the axis of and revolving bodily as a unit with a rotatable twisting drum, the auxiliary capstan being disposed between a plurality of wire supply sources independently rotatable upon the twisting drum and a main capstan which serves to feed the completed cable to a take-up reel. The speed of the auxiliary capstan which cooperates with the main capstan to exert a draft upon the wires is such that the individual wires are drawn from their supply sources at a speed in excess of the cable production speed or the speed of the main capstan, thereby tending to draw the wires from their supply sources at a greater speed than is necessary. However, this does not occur since the wires slip upon the drums of the auxiliary capstan when the difference in tension on the wire on the supply and take-up sides of the auxiliary capstan reaches a predetermined point. The grooved peripheral surfaces of the drums may be freely turned during the threading thereof due to a pawl and ratchet mechanism. An enclosing housing or guard surrounding the greater portion of the peripheral surface of each drum prevents the displacement of the wires in the grooves, the wires passing through corresponding individual openings and the guard being shiftable to facilitate the threading of the wires therethrough.

Other objects and advantages of this invention will more fully appear from the ac-

companying detailed description taken in connection with the accompanying drawings, in which

Fig. 1 is a fragmentary schematic plan view of a telephone cable stranding apparatus embodying the features of this invention;

Fig. 2 is an enlarged fragmentary side view thereof, partly in section;

Fig. 3 is an enlarged vertical section partly in elevation on the line 3—3 of Fig. 2;

Figs. 4, 5 and 6 are sections on the lines 4—4, 5—5 and 6—6, respectively, of Fig. 3, and

Fig. 7 is a reduced partial section on the line 7—7 of Fig. 3.

This invention will be described in connection with a wire twisting or stranding apparatus, such as is used in the manufacture of telephone cables. In order to simplify the disclosure of this invention only such elements of a stranding apparatus have been shown, as are necessary to a full and complete understanding thereof. For a more complete illustration and description of a stranding apparatus, particularly the stranding or twisting drums (not shown) carrying the wire supplies, which generally are coiled upon reels, with which the apparatus of this invention is particularly applicable, reference may be had to Patent 1,579,769 to H. F. Jones, dated April 6, 1926, wherein one of such twisting drums is illustrated.

Referring now to the drawings in detail, the numeral 10 indicates a portion of the right end of a stationary frame upon which may be revolvably journaled several twisting drums (not shown), the frame also providing a journal for a hollow rotatable shaft 11 which projects from the frame 10 and has fixed to rotate therewith an auxiliary capstan 12, the shaft being driven from a suitable source of power (not shown). A telephone switchboard cable of the flat type is illustrated in the drawings as being formed, the pairs of wires 13 being stranded or twisted about a thin flat press-board core 14, which in the operation of the stranding apparatus is advanced toward the right as viewed in Figs. 1 and 2 at a predetermined rate upon a stationary shelf or support, the core 14 passing along the axis of the twisting drums and the auxiliary capstan 12 and then through a central aperture 15 formed in a rotary distributor plate 16 of the usual

form, provided with a plurality of wire distributing apertures. A polisher or compacting sleeve is indicated at 17 which is provided with an aperture having a contour corresponding to the shape of the finished cable, which may be drawn therethrough by a usual capstan mechanism 18 (Fig. 1). Mounted axially upon the frame 10 is a hollow spider bra ket 19, one arm 20 of which is shown secured by a screw 21 to the frame 10 and, secured axially upon the bracket 19 as indicated at 23, is a stationary ring gear 24 having external teeth. Attached to the extreme right end of the shaft 11 by a key 25 (dotted lines Fig. 4) is a circular bearing plate 26 upon which is journaled a pair of horizontal diametrically opposed shafts 27 each having fixed upon its left end a spur gear 28 which meshes with the ring gear 24 (Fig. 4). The left end of each of the shafts 27 rotates in a radial thrust ball bearing 29 retained in position upon the plate 26 by a circular cover plate 30, while the right end thereof rotates upon a radial ball bearing 31 secured within a bracket 32 fixed to the plate 26, each of the shafts 27 having fixed thereon intermediate the ball bearings a bevel pinion 35. The shafts 27 each drives a pair of capstan drums 36, each capstan being freely rotatable upon a relatively stationary shaft 37 extending at right angles to each other and also to the shafts 27, through bevel gears 38 secured to adjacent end faces of the drums (Fig. 3). Each of the bevel pinions 35 carried upon the shafts 27 meshes with a bevel gear 39 secured to the end face of one of the drums 36 comprising each pair. One end of each of the shafts 37 is supported in the brackets 32, while the opposite ends thereof are supported in brackets 40 fixed to the plate 26. Set screws 41 threaded into the brackets 40 serve to hold the shafts stationary relative to the brackets, the drums 36 rotating upon ball bearings similar to the bearings 29 and 31 mounted in opposite ends of the drums. The distributor plate 16, as clearly shown in Fig. 4, is mounted for rotation with the capstan 12 by four studs 42 (Figs. 3 and 4) threaded at their left ends into the brackets 32 and 40, the plate being adjustable upon the studs longitudinally thereof as indicated at 43 (Fig. 4).

To facilitate the threading of the wires around each of the capstan drums 36 in stringing the stranding apparatus, a sleeve 44, provided with a plurality of similarly radially disposed peripheral grooves 45, is mounted for independent rotation upon separated peripheral surfaces of each of the drums 36. The sleeve 44 is retained from longitudinal displacement upon its associated drum 36 by an annular peripheral flange 46 formed upon one end of the drum which engages within an inner annular shoulder provided in the corresponding end of the sleeve, the opposite end face of the sleeve abutting the end face of a

hub portion of the associated bevel gear 38 (Fig. 3). Formed in the inner annular face of the sleeve 44 at the end thereof which is associated with the bevel gear 38 are ratchet teeth 47 (Fig. 7), a spring pressed pawl 48 pivoted within a depression 49 provided in the corresponding end of the drum 36 forming a driving connection between the drum and the sleeve when the stranding apparatus is in operation. This action it is believed will be clear by referring to Fig. 7, the drum 36 rotating in the direction indicated by the arrow. During the threading operation, which will be described shortly hereinafter, it will be apparent that the sleeve 44 may be rotated in the same direction independently of the drum which is stationary at this time, the pawl 48 merely idly riding into and out of the ratchet teeth 47. Closely surrounding the greater portion of the peripheral surface of each sleeve 44 is a shiftable circular housing or guard 51 formed from steel tubing as clearly shown in Fig. 6. The guard is rotatably supported in a sleeve like holder 52 secured at one end to a bracket 53 by screws 54 (dotted lines Fig. 3), which in turn is fixed to the bracket 40 by screws 55, one of each of the screws 54 and 55 being indicated in Fig. 3. Attached to the outer peripheral surface of the guard 51 intermediate its ends is a plate 56 carrying a stud 57 (Fig. 6). Carried upon the stud 57 is a handle 58 and surrounding the stud between the plate 56 and a head 61 formed upon the outer end of the stud is a coiled compression spring 62. An inner end circular face of the handle is designed to be retained in either of two operated positions of the guard 51 in suitable depressions 63 formed in a raised peripheral surface of the holder 52, the spring 62 serving to hold it therein. The plate 56 in its movement with the handle 58 and guard 51 rides in a slot 64 of suitable length provided in the raised peripheral surface of the holder 52 (Figs. 3 and 6), the depressions 63 being formed adjacent opposite ends thereof. The holder 52 upon its right and lower sides as viewed in Fig. 6 is provided with a comparatively wide slot 65 which extends almost half way around the holder 52. The guard 51 upon its right side Fig. 6 is provided with a slot 66 similar in width to that of the slot 65 and which extends around the periphery of the sleeve 44 for a relatively short distance sufficient only to permit the wires 13 to pass onto and off of the sleeve. Fixed to the outer peripheral surface of the sleeve 44 at opposite sides of the slot 66 are hardened steel guide plates 67 and 68 provided with a plurality of openings 69 corresponding in number with the grooves 45 and aligned therewith for the passage of the wires 13 onto and off of the capstan sleeve 44. In the position of the guards 51 as viewed in Figs. 3 and 6 it will be assumed that the auxiliary capstan 12 has been thread-

ed with the wires 12, although for the sake of simplicity the wires have been omitted from Fig. 3. To re-thread the plurality of capstan sleeves 44 with the wires 13, the capstan 12 is rotated through the movement of the shaft 11 to position the individual capstans 44, one after the other in the position occupied by the left hand capstan 44 as viewed in Fig. 3. In this position the attendant while 10 the apparatus is at a standstill rocks clockwise the guard 51 from the full line position to the dotted line position as viewed in Fig. 6, which movement amounts to approximately 75°. This is accomplished by first pulling 15 outward on the handle 58, against the action of the spring 62, until the inner circular face thereof has left the depression 63 of the holder 52 and thereafter rocking it clockwise until it latches into the other depression 63 as here- 20 before described. In this position it will readily be apparent that the openings 69 in the guide plates 67 and 68 will be moved from a position in which they extend parallel to the axis of the capstan 12 to a position substan- 25 tially at right angles thereto at the right end thereof as viewed in Fig. 3, in which position the threading operation may readily be performed. The wires 12 are drawn from the supply reels carried upon the twisting drums 30 (not shown) passed through the hollow shaft 11 and along the axis of the capstan 12, threaded through the openings 69 in the guide plate 67 and into the corresponding grooves 45 of the sleeve 44 and guided therearound by 35 the guard 51. Upon emergence from the grooves the wires are threaded through the corresponding openings 69 in the guide plate 68 and a suitable length drawn therethrough. One or several turns may be taken around the 40 sleeve depending upon the desired range of tension at which the wires are to be delivered to the stranding or twisting point, which it will be apparent is between the distributor plate 16 and the compacting sleeve 17. The 45 guard 51 is then returned to its full line or operating position (Fig. 6) in a reverse manner to that just described. The capstan 12 is then rotated clockwise until the lower capstan sleeve 44 as viewed in Fig. 3 is in the 50 position previously occupied by the capstan sleeve just previously threaded, whereupon it is threaded in a similar manner and so on until all four of the sleeves have been threaded. The wires 13 are then drawn from the 55 sleeves 44, which at this time are free to rotate, through the action of the pawl and ratchet mechanism, as hereinbefore described, threaded through their respective apertures in the distributor plate 16, through the compacting sleeve 35 around the core 14 which 60 has previously been threaded through the apparatus from a suitable supply (not shown) positioned at the left end of the twisting drums (not shown). A suitable number of 65 turns of the core and wires are taken around

the capstan 18, the end thereof being attached to a suitable take-up device or reel (not shown).

It will be apparent upon threading the stranding apparatus in the aforementioned 70 manner and causing the hollow shaft 11 and the capstan 18 to rotate in the direction indicated by the arrows Figs. 3 and 1, respectively, that the capstan drums 36 with their attached sleeves 44, through the gears 28 roll- 75 ing around the stationary ring gear 24, bevel pinions 35 meshing with the bevel gears 39 and the meshing sets of bevel gears 38 will rotate in unison upon the stationary shafts 37 in the direction indicated by the arrows 80 (Figs. 2, 3 and 6), in addition to their rotation as a unit with the shaft 11. Thus the pairs of wires 13 are individually drawn from their respective supply reels (not shown) through the cooperation of the capstans 12 85 and 18 and fed to the compacting sleeve 17, the capstan 18 serving to draw the completed or stranded cable through the compacting sleeve 17 and feed it to the take-up mechanism (not shown). Due to the fact that the loaded 90 supply reels do not always contain the same amount of wire, their weights differ, consequently the pull in pounds necessary in one particular structure to unwind the wire therefrom at times varies from 0 to 15 pounds. 95 This wide range of tension on the wires is also accentuated by the generally unbalanced condition of the reels due to various causes other than their differences in weight. The peripheral speed of the capstan sleeves 44 relative 100 to the capstan 18 is such that there is a tendency to pull the paired wires 13, which in the embodiment illustrated consist of forty-four pairs, eleven pairs for each sleeve 44, at a greater speed than is necessary, that is, 105 in comparison to the speed at which the cable is produced or drawn from the compacting sleeve 17 by the capstan 18. It will be apparent, however, that this does not occur since the coil of wire around the groove 45 of the 110 sleeve 44 slips when the difference intension on the wire on the supply and take-up sides thereof reaches a predetermined point, which point is primarily governed by the number of 115 wraps of the wire around the capstan sleeve 44. This action of the capstan 12 it will be apparent provides a substantially uniform predetermined range of tension on each pair of wires and an equal tension in all the pairs at the point of formation thereof into the 120 cable, the pull of the capstan 18 upon the completed cable being only sufficient to provide the necessary friction between the auxiliary capstan 12 and the wires passing therearound to cause the two capstans to properly co- 125 operate and to pull the completed cable through the compacting sleeve 17. The net result of interposing the auxiliary capstan 12 between the wire supply reels and the main capstan 18 is that the pull of the latter cap- 130

stan does not submit any single pair of wires or the plurality of wires at the point of formation into the cable or the completed cable itself to any deleterious tensions.

5 The auxiliary capstan, as hereinbefore described, is particularly useful in stranding wires around irregular or noncircular cores, wherein the tension on the wires due to the varying point of application of the wire to the core during the stranding operation results in the subjection of the wires to unequal tensions which may sometimes tend to result in a nonuniform distribution of the wires and also may tend to considerably distort the core. Although the apparatus is described and illustrated in connection with the forming of oval and flat type switchboard cable, it will be apparent that it may be used equally well in the forming of circular type cables.

20 What is claimed is:

1. In a material working apparatus, material working means, a single element for individually feeding materials thereto under an equal tension within a predetermined range, means cooperating with the feeding element to maintain the necessary friction between the material and the element and for moving the worked material from the working means, the material moving means permitting the material to slip on the feeding element when the tension on the material at opposite sides of the element reaches a predetermined point, and means for operating the material feeding element and the worked material moving means at different predetermined speeds.

2. In a material working apparatus, material working means, a single element about which the material and the worked material is wrapped positioned at each side of the point of working the material and cooperating to individually feed materials to the working point under an equal tension within a predetermined range and for moving the worked materials therefrom, the material slipping on one of the feeding elements when the tension on the material at opposite sides of the element reaches a predetermined point, and means for operating the elements at different predetermined speeds.

3. In a material working apparatus, material working means, a single element about which the material is wrapped for individually and collectively feeding materials to the working means under an equal tension within a predetermined range, means cooperating therewith to vary the friction between the materials and the feeding means for causing the latter means to function and for moving the worked materials collectively from the working means, and means for operating the material feeding element and the cooperating means at different predetermined speeds.

4. In a cable stranding apparatus, the combination with a rotatable member thereof and

a plurality of strand supplies, means for moving the completed cable, and a single rotatable element carried by the rotatable member about which the strands are individually wrapped for feeding the strands to the point of formation thereof into a cable under an equal tension within a predetermined range, the strands slipping on the feeding element when the tension on the strands at opposite sides of the element reaches a predetermined point.

5. In a cable stranding apparatus, the combination with a rotatable member thereof and a plurality of strand supplies, means for moving the completed cable, a plurality of rotatable elements carried by the rotatable member about each of which a separate group of the strands are individually wrapped for feeding the strands to the point of formation thereof into a cable under an equal tension within a predetermined range, the cable moving means and the strand feeding elements in cooperation tending to feed the strands to the point of formation thereof into a cable at a greater speed than the completed cable is moved, means for operating the cable moving means, and means operatively connecting the rotatable member and the elements carried thereby for rotating the elements.

6. In a cable stranding apparatus, the combination with a rotatable member thereof and a plurality of strand supplies, means for moving the completed cable, a plurality of elements carried by the rotatable member about each of which a separate group of the strands are individually wrapped in a plane parallel to the axis of rotation of the stranding apparatus, the cable moving means and the feeding elements cooperating together to individually feed the strands to the point of formation thereof into a cable under an equal tension within a predetermined range and for moving the completed cable, and means for operating the cable moving means and the feeding elements at different predetermined speeds.

7. In a material working apparatus, a rotary strand feeding means around which material may be wrapped, and a shiftable housing for preventing the displacement of the material from within the groove and for facilitating the threading of the material therearound.

8. In a material working apparatus, a rotary drum, a sleeve surrounding the periphery thereof around which material may be wrapped, and means for operatively connecting the sleeve to the drum during rotation of the latter and for permitting independent rotation of the sleeve upon the drum.

9. In a material working apparatus, a rotary strand feeding means provided with a peripheral groove around which material may be wrapped, a rotatable housing mount-

- ed around substantially the entire periphery thereof for preventing the displacement of the material from within the groove, means for rotatably shifting the housing upon the 5 rotary means into a plurality of positions, and means cooperating with the latter means for maintaining the housing in a set position.
10. In a strand working apparatus, a rotary drum, a sleeve surrounding the periphery thereof and provided with a plurality of peripheral grooves around which individual strands may be wrapped, means for operatively connecting the sleeve to the drum during rotation of the latter and for permitting independent rotation of the sleeve upon the drum, and a shiftable and latchable housing operatively mounted around substantially the entire periphery thereof for preventing the displacement of the strands 15 from within the grooves and for facilitating the threading of the strands therearound.

11. In a cable stranding apparatus, the combination with a rotatable member thereof and a plurality of strand supplies, means for causing the strands to be formed into a cable, 25 means for moving the completed cable, a plurality of strand feeding devices carried by the rotatable member and equally disposed about the axis thereof for feeding the strands to the point of formation thereof into a cable 30 under an equal tension within a predetermined range, each device comprising a single rotatable element capable of supporting a plurality of strands individually wrapped therearound in spaced relation, means for 35 operating the cable moving means, and means operatively connecting the rotatable member and the strand feeding devices carried thereby for operating the latter.

In witness whereof, I hereunto subscribe 40 my name this 14th day of August, A. D. 1926.

THORNTON McDUFFEY YANCEY.
